UNITED STATES PATENT OFFICE.

JOSEF SKÁLA, OF PLZEN, CZECHOSLOVAKIA.

TOY SHOOTING DEVICE.

Application filed July 16, 1923. Serial No. 651,933.

To all whom it may concern:

Be it known that I, JOSEF SKÁLA, a citizen of Czechoslovak Republic, residing at Plzen, Skvrnany, Czechoslovakia, have invented a new and useful Toy Shooting Device, of which the following is a specification.

The present invention relates to a toy shooting device in which a tension spring 10 constitutes the projectile and consists in providing the same with a carrier extending the whole length of the spring when this is stretched, a releasable holding device to engage one end of a spring projectile of 15 helical or spiral form and a part at the end of the carrier against which the other end of the spring projectile abuts while it is being stretched.

Two forms in which the present invention 20 may be carried into effect are illustrated in the accompanying drawings, as examples.

Figs. 1 and 2 show two views of one form of a spring projectile in an unstretched condition,

25 Fig. 3 is a side view of a modified form, Fig. 4 is a side view of a pistol for firing the projectile,

Fig. 5 is a broken longitudinal view of a toy gun,

30 Fig. 6 is a plan view of the gun as seen from the under side,

Fig. 7 is a cross-sectional view on the line VII—VII in Figs. 5 and 6,

35 Fig. 8 is a detail view of the back-sight, and

Fig. 9 is a plan view of a projectile for the gun.

Referring to Figs. 1 to 3 the spring 1 constituting the projectile is given outwardly the form of either a cone with the apex at the forward end (Fig. 2) or of a cylinder (Fig. 3). The first coil of the spring leaves a free central opening 2 while the last coil is bent so as to provide two 45 lateral outstanding loops 3 which serve as grips for stretching the spring.

Such a spring projectile can for example be put under tension upon a finger placed inside and then shot off by releasing it. It 50 is more advantageous however to employ a toy arm as for example a pistol or gun for shooting. As shown for example in Fig. 4 a pistol is provided with a forwardly extending carrier stem 4 which is either conical as shown in full lines or cylindrical as shown in dotted lines and the stem is pro-

vided at its forward end with a point 5 of reduced diameter which enters the opening 2 in the spring so that the forward end of the spring is held back by the engagement of the first coil against the shoulder on the end of the stem. The spring 1 is stretched along the stem 4 until the loops 3 on the last coil of the same pass over noses 6 upon a double ended latch whereby the 60 spring is secured. The double latch is mounted in a recess 8 in the pistol grip 7 upon a pivot 9 and by a downward extension 10 constitutes the trigger. The trigger spring 11 is fastened to the grip 7 so as to 65 constitute at the same time the trigger bow.

In place of a conical or cylindrical spring 1 a spiral spring might also be employed. The pistol or the like can also be provided with a barrel covering the stem 4. It would 70 however also be possible to employ such a barrel as a direct outer guide for a spring projectile to be inserted therein. In this case the forward end of the latter could be provided with laterally projecting abutments and if the barrel be undivided, a fork or the like could be employed for stretching the spring or the barrel could be provided with longitudinal slots for the side loops 3 of the spring 1.

After drawing the trigger 10 the spring 1 while guided by the stem 4 closes together and by virtue of its own energy continues in flight so that the closed spring constitutes a projectile. Such a projectile however remains elastic and strikes the mark softly so that no wounding or damage takes place at the spot which is struck.

Referring to the development of the subject-matter of the invention in the form 95 of a child's gun shown in Figs. 5 to 9, a barrel 20 is secured to a butt 7 (Figs. 5 and 6) and within the barrel is concentrically arranged a carrier stem on rod 4¹ the rearward end of which is secured to the 100 butt 7 while the forward end thereof is left free and provided with a pin 5¹ of reduced diameter. The barrel 20 has on its under side a slot 21 extending over almost the whole length of the barrel. On one side 105 of the slot recesses 22 are provided serving as rests for the shooting device. This device is arranged on a guide ring 23 which surrounds the barrel 20 and is guided in the slot 21 by inwardly projecting ends 24 110 (Fig. 7). Between the ends 24 a trigger 10¹ is pivotally mounted upon a pin 9¹ its

angle of movement being limited by a pin 25 inserted in a slot 26 (Fig. 5). The trigger 10 is held by a spring 11 which constitutes at the same time the trigger bow 5 and which is connected on the one hand with the trigger and on the other hand with the guide ring 23. The trigger is provided with a hook 6¹ for engaging and stretching the spring projectile. Lateral projections 27 are provided on the guide ring 23 to enable the ring to be readily grasped.

In the butt 7 a vertical guide passage 28 is provided which registers with an opening 29 in the barrel 20 in which opening 15 projects however a pin 30 formed out of the material of the barrel. In the guide 28 is provided a sighting device 31 in the form of a strip of metal having a series of adjusting holes 32. The upper end of 20 the strip is widened and provided with a sighting notch. At the forward end of the barrel 20 is located the foresight 34 (Fig. 5).

The projectile 1 (Fig. 9) has the form 25 of a cylindrical helical spring the ends being reduced in diameter or rounded off and the forward end being provided with an opening 2 for the reception of the pin 5¹. At the rearward end of the spring an 30 axially extending loop 35 is formed.

For shooting, the projectile is so placed in the barrel 20 that its forward end butts against the shoulder on the free end of the rod 4. The trigger and cocking device is 35 pushed forward along the barrel 20 until the hook 6¹ engages in the loop 35. The free end of the hook 6¹ lies close to the side of the rod 4 (Figs. 5 and 7) so that the loop 35 when engaged cannot slide off 40 the hook. The trigger device is then grasped by the projections 27 and drawn back and in so doing the projectile 1 is put under tension by the hook 6. When the desired tension of the spring has been attained 45 the trigger device is slightly rotated until the inner portions 24 of the same engage in one of the side recesses 22 provided in the slot in the barrel 20, whereupon, the projections 27 being released, the trigger device 10, 23 is secured in the adjusted position, since it is pressed against the end wall of the recess—which is preferably undercut—by the pull of the spring 1.

Upon pulling the trigger 10 the hook 6¹ 55 releases the loop 35, the projectile is drawn together and shoots forward owing to the stored up energy which is thus released, the range depending upon the selected tension of the spring 1, that is to say, upon the 60 position of the trigger device 10, 23 upon the barrel 20 that may have been selected. Thus it is possible, where the range is necessarily short, as for example in a small room, to adjust the energy of the projectile and 65 so avoid injury to the object struck; where-

as for longer ranges, the energy of the projectile can be correspondingly increased. In accordance with the range the sighting device 31 is vertically adjusted by passing the pin 30 through one of the holes 32. 70

In order to ensure that the loop 35 shall slide off the hook 6¹ on the trigger 10¹ in a proper manner, the inner ends of the parts 24 of the guide ring 23 are extended as far as the under side of the loop 35 75 (Fig. 5) when this is hooked, so that they support the loop as the trigger 10¹ is pulled until the loop is released by the hook 6¹.

The slot 21 in the barrel can be carried 80 so far forward that when the guide ring 23 is in its most forward position the hook 6¹ is located in the mouth of the barrel and the loop 35 of the projectile can consequently be easily hooked on. The guide ring is then first drawn back whereupon 85 the forward end of the projectile is pulled over the end 5¹ of the rod.

The toy shooting device according to this 90 invention is primarily intended for children; by a suitable modification it can however also take the form of a small gun or of a pistol. A construction may also be chosen in which the rod 4¹ is omitted and the spring 1 has lateral projections or the like adapted to abut against the end of the 95 barrel.

In certain cases the spring may be provided at its forward end with a covering cap of a spherical or like form or other shell 100 differently shaped and fixed.

I claim:

1. A shooting device, comprising a coiled 105 spring projectile, a carrier concentrically disposed relatively to the projectile, said carrier affording an abutment for engagement by the forward end of the projectile, means for applying tension to the projectile in opposition to the abutment and means for releasing the tensioned projectile.

2. A shooting device, comprising a coiled 110 spring projectile, means extending axially through the projectile affording an abutment for engagement by the forward end of the projectile, means for applying tension to the projectile in opposition to the abutment and means for releasing the tensioned projectile. 115

3. A shooting device, comprising a coiled 120 spring projectile, a carrier concentrically disposed relatively to the projectile, said carrier affording an abutment for engagement with the forward end of the projectile and means, including a trigger, operable to tension the projectile in opposition to the abutment and for releasing the same. 125

4. A shooting device comprising a coiled 130 spring projectile, a carrier concentrically disposed relatively to the projectile, an abutment at one end of said carrier for the first coil at the forward end of the projectile, 135

- a butt on the other end of the carrier, a catch pivoted in the butt to engage the last coil at the rearward end of the projectile when the projectile is under tension and a 5 spring-controlled trigger device to normally hold the catch in the engaged position, substantially as set forth. 55
5. A shooting device comprising a coiled spring projectile, a carrier for the projectile, an abutment at one end of said carrier for the first coil at the forward end of the projectile, a butt on the other end of the carrier, a pivoted catch adapted to engage the last coil at the rearward end of the projectile, 10 a spring-controlled trigger for operating said catch, means whereby the trigger and catch can be moved longitudinally along the carrier, means of detachably holding said catch in position against the tension of the 15 projectile and means for sighting along the carrier, substantially as set forth. 60
6. A shooting device comprising a coiled spring projectile, a barrel for said projectile, a fixed rod centrally located in the 20 barrel and forming a carrier, an abutment at the forward end of said rod for one end of said projectile, a pivoted catch adapted to engage the last coil of the projectile, a spring-controlled trigger to operate said 25 catch, a slide to which said catch and trigger are pivoted, means of traversing said slide along said barrel, means of releasably holding said slide in a position to maintain said spring under the desired tension, a butt on 30 the rear end of the barrel and fore and back sights, substantially as set forth. 70
7. A shooting device comprising a coiled spring projectile, a barrel for said projectile, a longitudinal slot in said barrel, a 35 butt on the barrel, a rod fixed in the butt and extending centrally through said barrel so as to form a carrier, an abutment at the forward end of said rod for one end of the projectile, a split ring slidably surrounding 40 the barrel, spaced inwardly directed extensions on the ring projecting through the slot in the barrel, a catch pivoted between said extensions to engage the last coil at the rearward end of the projectile, a spring-controlled trigger to normally maintain the 45 50
- catch in engagement with the projectile, recesses in the slot in the barrel to engage said extensions when said ring is turned to hold the projectile under tension, substantially as set forth. 65
8. A shooting device comprising a coiled spring projectile and a carrier for the projectile constituting a fixed abutment for the forward end thereof, the coils at the forward end of said projectile being gradually reduced in diameter substantially as set forth. 60
9. A shooting device comprising a coiled spring projectile, coils of gradually increasing diameter at the forward end of said projectile, coils of equal diameter following said forward end, and a carrier for the projectile adapted to form a fixed abutment for the forward end of the projectile substantially as set forth. 65
10. A shooting device comprising a coiled spring projectile, coils of gradually increasing diameter at the forward end of said projectile, coils at the rear end thereof of gradually decreasing diameter and intermediate coils of equal diameter, and a carrier for the projectile adapted to form a fixed abutment for the forward end of the projectile substantially as set forth. 70
11. A shooting device comprising a coiled spring projectile, a carrier concentrically disposed relatively to the projectile, means whereby the projectile can be stretched, means for holding the projectile under tension and means for releasing the projectile when under tension substantially as set forth. 80
12. A shooting device comprising a coiled spring projectile, a carrier for the projectile, a butt on the carrier having a vertical guide passage, means for sighting along the carrier comprising a back sight adjustably mounted in said passage, means whereby the projectile can be stretched and means for releasing the projectile when under tension 85
- substantially as set forth. 90
